COIN WRAPPER CUTTING UNIT

George J. Bentz, Sr., % Veterans Administration, General
Delivery Branch, Los Angeles, Calif.

Filed Aug. 12, 1963, Ser. No. 76,175

Term of patent 14 years

(Cl. D55—1)

The broken line showing of a coin wrapper in FIGURE 3 is for illustrative purposes only.

I claim:

The ornamental design for a coin wrapper cutting unit, substantially as shown and described.
